UNITED STATES PATENT OFFICE.

ADELBERT F. COOK AND LLOYD R. REED, OF URBANA, OHIO, ASSIGNEES TO THE W. B. MARVIN MANUFACTURING COMPANY, OF URBANA, OHIO, A CORPORATION OF OHIO.

BUTTON-SETTING MACHINE.

1,374,360.

Specification of Letters Patent. Patented Apr. 12, 1921.

Application filed August 20, 1917. Serial No. 187,170.

To all whom it may concern:

Be it known that we, ADELBERT F. COOK and LLOYD R. REED, citizens of the United States, residing at Urbana, in the county of 5 Champaign and State of Ohio, have invented certain new and useful Improvements in Button-Setting Machines, of which the following is a specification.

This invention relates to machines for setting buttons on shoes.

An object of the invention is to simplify the construction of machines of the character referred to and make the same more effective in operation.

15 A further object of the invention is to improve the arrangement and construction of the chutes or raceways which convey the buttons from the hopper to the stapling mechanism whereby the machine may be 20 quickly and easily adapted for setting odd sized buttons without removing any of the parts.

A further object of the invention is to improve the button and wire feeding devices 25 to provide an arrangement whereby the button will be fed to the stapling mechanism and the wire threaded therethrough upon the initial movement of the main operating device to obviate the necessity of removing 30 a button and the wire which has been threaded thereto in the event that it is desired to adjust the machine for the purpose of setting special sized buttons.

A further object of the invention is to 35 provide an arrangement to reduce the power necessary to operate the mechanism.

A further object of the invention is to improve the cut-out devices for the wire feed.

In the accompanying drawings:—

40 Figure 1 is a side elevation of a machine embodying my improvements shown mounted upon the supporting pedestal.

Fig. 2 is a front elevation of the machine.

Fig. 3 is a side elevation with one-half of 45 the hopper removed.

Fig. 4 is a detail of a portion of the agitating and feed wheel.

Fig. 5 is a detail section of a portion of the feed wheel and part of the operating 50 mechanism for the same.

Fig. 6 is an elevation of the opposite side of the machine from that shown in Fig. 3.

Fig. 7 is a detail showing the kick-out for the buttons.

Fig. 8 is a top plan view showing the 55 parts in normal position.

Fig. 9 is also a top plan view showing the parts in position for setting odd sized buttons.

Fig. 10 is a longitudinal section showing 60 the main operating device, the normal inoperative position of the same being shown in full lines and what will be called the second position in dotted lines.

Fig. 11 is also a longitudinal section showing 65 the same parts, the third position of the main operating device being shown in full lines and the fourth position in dotted lines.

Fig. 12 is a side elevation showing the 70 final button feed devices.

Fig. 13 is a top plan view of the cut-out devices for the wire feed.

Fig. 14 is a section of a portion of the cut-out devices for the wire feed, the section being on the line 14—14 of Fig. 15.

Fig. 15 is also a section of a portion of the cut-out devices for the wire feed, the section being on the line 15—15 of Fig. 14.

Fig. 16 is also a section on the line 14—14 75 of Fig. 15 showing the parts in a different position.

Fig. 17 is a top plan view of the stapling mechanism and a portion of the wire feeding mechanism.

Fig. 18 is a top plan view of the hopper 80 with the lid partly open.

Fig. 19 is a detail section of a portion of the shifting devices for the raceways.

Referring to the drawings, (Fig. 1) 1 represents the pedestal upon which the operating devices are supported, the upper end of the pedestal being provided with a base board 2 to which the casing 3 is secured; the casing being preferably cast in a single piece cored out to receive a portion 90 of the operating devices.

Hopper and feed wheel.

The hopper for the buttons is represented by 4, the hopper being preferably formed in 100 two halves and provided with an upper hinged lid 5. The bottom of the hopper is provided with a lug 6 hinged upon the cross rod 7 (Figs. 3, 9 and 10) which extends between and is supported by the rearwardly extending ears 3^a of the casing 3, the distance between the ears 3^a being greater than the width of the lug 6 so

that the hopper may be moved laterally for a purpose hereinafter to be explained. Mounted in the hopper is a feed and agitating wheel 8 (Figs. 3, 4, 5 and 18) which is provided with a series of equally spaced fingers 9 which extend to the inner periphery of the hopper, the interior of the hopper being circular in form. The feed wheel is journaled upon a stud 10 which is secured to one side of the hopper, the feed wheel lying closely against that side of the hopper. The forward side of each finger 9 is grooved or cupped out as indicated at 9^a, the bottom of the groove being inclined inwardly toward the side of the casing.

Means are provided for imparting to this feed wheel an intermittent motion upon each operation of the machine. As shown in Figs. 3, 4, and 5, one side of the wheel proper 8 is provided with a series of recesses 11. The forward side of each recess is formed with a slightly tapered face as shown in Fig. 5 and the bottom and rear wall of the recess with a pronounced incline. Slidably mounted in a groove 12^a formed on the outside of the hopper which is closed by a plate 12, Figs. 5, 6, and 7, is a rod 13, the upper end of which carries a small housing 14 in which is slidably mounted a pin 15, normally pressed outwardly by the spring 16, interposed between the head of the pin and the adjusting plug 17 in the end of the housing, the head of the pin forming a stop to limit the outward movement of the pin; this housing being provided with a reduced bore in which the pin slides and the head of the pin being adapted to abut the shoulder formed by this reduced bore in a manner which will be clear, as shown in detail in Fig. 5. The lower end of this sliding rod 13 is provided with a cam roll 18 (Figs. 10 and 11) which rides in a camway 19 of a main operating lever 20, which lever will be referred to more in detail hereinafter, it being sufficient to state here that when this lever is operated the sliding rod 13 will be thrown upwardly so as to impart a partial revolution to the feed wheel by reason of the engagement of the pin 15 in one of the recesses 11, the pin riding out of the recess by reason of the inclination thereof upon the return of the main operating lever to normal position; a spring-pressed stop pin 21, similar to the pin 15, located in the wall of the hopper, being preferably provided to prevent backward rotation of the feed wheel. As shown in Fig. 18 the upper portion of that side of the hopper adjacent the feed wheel is laterally off-set, as indicated at 4^a, and provided with a downwardly inclined groove 22 (see also Fig. 3).

In operation at each partial revolution of the feed wheel a quantity of buttons will be thrown into this groove. Some of the

buttons will be deposited in such a manner that their eyes will enter the groove and thus retain the buttons on the downwardly-inclined off-set portion of the hopper, while the balance of the buttons will again fall back into the bottom of the hopper; these buttons being directed to the side and bottom of the hopper by a guide or guard 23 (Figs. 3, 7, and 18), the guard extending diagonally across the lower end of the groove 22 and being secured to the lid of the hopper so that when the lid is raised free access may be had to the lower end of the groove for the purpose of removing any buttons which may have become clogged therein; the guard being positioned sufficiently above the grooveway to allow the passage of any buttons whose eyelets have become properly lodged in the groove, but obstructing the passage of all other buttons.

As an additional safeguard to prevent the buttons from clogging in the event that a button should become lodged against the guard 23 in such a way as to prevent its falling back into the hopper, I have provided a "kick-off" (Figs. 3, 6 and 7). This kick-off is in the nature of an arm 24 pivoted on the stud 25 secured to the side of the hopper, the free end of the arm has an upwardly projecting finger 26 and the opposite end thereof a downwardly extending tail 27 having a finger 28. A spring 29 coiled about and secured to the stud 25 and having its free end bearing against the small lug 30 on the arm, normally tends to project the finger 26 up through the slot 22 just in front of the guard 23, as shown in Figs. 3 and 7. The finger 28 normally lies against the edge of the operating rod 13, so as to hold the finger 26 in retracted position, as indicated in Fig. 6, but as the rod 13 is operated the finger 28 will ride into a recess 13^a in the rod 13 allowing the spring 29 to project the finger 26 up through the open slot 22 and kick off any button which has become lodged in front of the shield. This operation takes place not only upon the up-stroke of the operating rod 13 but also on the return thereof to normal position.

Button chutes and shifting means therefor.

Leading from the lower end of the grooveway 22 to the stapling mechanism is a downwardly inclined raceway 31 preferably formed integral with the hopper (Figs. 3 and 6). This raceway is provided with two separate covers 32 and 33. (Figs. 2, 3, 6, 8, 9 and 18). That portion of the raceway beneath the cover 32 forms a continuation of the groove 22 and is provided with a groove 34 to receive the eyes of those buttons which enter the groove 22. The portion of the raceway under the cover 33 is also provided with a grooveway 35 to receive buttons of

larger size, commonly known as odd buttons, the cover 33 being of larger dimension than the one 32. In the construction shown, for manufacturing purposes, each of the covers 5 it at its lower end shaped to form a floor 32^a and 33^a, these floors coinciding with the upper surface of the raceway so as to form a continuation thereof and being provided with grooves 32^b and 33^b which coincide with 10 and form a continuation of the grooves in the raceway proper; the lower ends of the covers above the floors being cut away as indicated at 32^c and 33^c. Each of the covers has secured thereto a double-pronged spring 15 tongue 36 the lower free ends of which project into the cut-away portions of the covers and extend to a point near the floor thereof so as to act as resilient retaining devices for the buttons, from beneath which the buttons 20 are fed one by one in the manner hereinafter to be described.

That portion of the raceway beneath the cover 32 is the one employed for conveying the buttons from the hopper, the buttons 25 placed in the hopper being the ones which are most commonly used. When it is desired to set the odd sized buttons with which that portion of the raceway beneath the cover 33 is equipped, provision is made for moving 30 the raceway laterally so as to bring the odd buttons in position to be threaded and set by the stapling mechanism in the following manner.

It has heretofore been explained that the 35 rear part of the hopper is hinged on the transversely extending rod 7 in such a way that it can be moved laterally thereon as well as swung rearwardly. Rotatably mounted in laterally-extending brackets 37 and 38 40 (Figs. 6, 8 and 9) secured to the main casing is an operating member consisting of a shaft 39 and a crank member 42, the rear end of which has an operating crank arm 40 and the forward end a crank arm 41. One portion 45 of the part 42 is in the nature of a disk 43 having a forwardly extending eccentric pin 44 (shown in dotted lines in Fig. 6). Projecting laterally from the side of the hopper at the rear end thereof is an arm 47, the 50 outer end of which is turned downwardly, as indicated at 47^a, and has on the rear side thereof a groove 47^b (shown in dotted lines in Fig. 6) into which the pin 44 extends. Extending laterally from the raceway is an 55 arm 48, the outer end of which carries a spring-pressed pin 49 (Fig. 19 for detail) provided with a finger piece 49^a, the pin being normally pressed into a recess 50 in the crank arm 41 by the spring 49^b; the 60 recess being in line with the pin 44 on the disk 43. As a result of this construction, when the member 42 and shaft 39 are rotated by the crank arm 40, the eccentric wrist pin 44, acting in the slot 47^b of the arm 47, throws 65 the hopper and raceways laterally so as to

bring the odd button raceway in proper working relation with the stapling devices, while the crank arm 41, by reason of its connection with the raceways through the spring-pressed pin 49 and arm 48, raises the 70 raceways upwardly so as to clear the eyes of the buttons in the raceway from the grooves; the mechanism being so timed that when the hopper and raceways have been moved laterally to the proper distance the 75 crank arm will allow the raceways to drop back to proper working position and bring the eyes of the odd buttons in proper position to be acted upon by the stapling mechanism. This operation throws out of commission 80 the feed and agitating wheel in the hopper by reason of the fact that the cam roller 18 is moved laterally out of the groove 19 of the main operating lever.

By reason of the connection described 85 between the arm 48 with the crank arm 41, the raceways and hopper may be tilted rearwardly by withdrawing the pin from the recess in the crank arm for the purposes of emptying the hopper or the raceways, and upon swinging the hopper back to normal position the pin 49 automatically enters the recess in the crank arm 41, to lock the hopper in position, the crank arm having an inclined face 41^a leading to the recess, (Figs. 6 and 8). 90 95

Final button feed.

It has been explained that after the buttons have passed down the raceway from the hopper they are retained by the spring 100 tongues 36 at the lower end of the raceway. The spring tongues are so located as to retain the lowermost button out of the path of travel of the wire. The first step upon the operation of the machine then is to feed 105 a button in position to be threaded by the wire which forms the staple, this being accomplished as follows:

Formed in the wall of the casing 3 is a downwardly inclined groeway 51 (Figs. 110 3 and 12). Slidably mounted in the groeway 51 is a carriage 52 having at each end thereof a laterally projecting bracket 53 and also having secured to the lower edge thereof a plate 54 which projects into the interior of the casing. Formed in the plate 54 is a vertically-extending slot 55 into which extends a straight faced stud 56 having a round pin 57 which is driven into the main operating lever 20 at the point shown in 115 Figs. 10, 11 and 12. Leading from the upper end of the slot 55 is a slot 58 which is concentric to the pivotal point 59 of the main operating lever 20. As a result of the construction as thus far described, upon the 120 initial movement of the main operating lever 20 the stud 56 will throw the carriage 52 downwardly in the groove 51 and at the proper time will ride into the concentric groove 58 so as to allow the main operating 125 130

lever an additional movement independent of the carriage to perform further functions to be described. Rotatably mounted in the brackets 53 of the carriage is a shaft 5 60 (Figs. 2, 3, 8, 9 and 12) to the forward end of which is attached a finger 61 which extends laterally to a point to bring its downturned end 61^a in a position to engage the lowermost button of the raceway; the 10 finger 61 being normally spring-pressed to engaging position by a spring 62 coiled about the shaft with one end thereof attached to the shaft and the other end engaged with one of the brackets 53. In the 15 normal inoperative position of the machine, the finger 61 is held out of engaging position by a stationary projection 63 attached to the main casing, the shaft 60 having for this purpose a bent end 60^a having a shoulder 20 60^b which engages the nose of the projection. In order to throw the shaft 60 in proper position to cause its bent end 60^a to engage the projection 63, there is provided at the side of the projection a pivoted lever 25 64 having a shoulder 64^a, the lever being provided with a spring 65 which tends to hold it in position to bring its shoulder into the path of the bent portion 60^a of the shaft when the parts are being returned to normal 30 position, which return movement is accomplished by a spring associated with the foot lever hereinafter to be described. As the parts return to normal position, the stud 56, striking the wall of the plate 54 at the 35 rear end of the slot 58 throws the carriage 52 rearwardly and causes the bent end of the shaft to engage the shoulder 64^a which pushes the lever 64 upwardly about its pivotal point and hence turns the shaft 60 40 against the tension of the spring 62 until the bent end of the shaft rides off of the shoulder of the lever, at which time it will be in a position to be engaged by the nose of the projection 63.

45 It should be explained that upon the initial movement of the main operating lever the bent end of the shaft 60 will ride off the nose of the holding projection, the spring 60 will throw the bent end 61^a of the finger 50 60 on top of the lowermost button in the chute and that the further travel of the carriage downwardly in the grooveway 51 will carry the button to proper position to receive the wire from the wire feeding devices now to be described.

Wire feeding devices.

Pivoted to a block 66 projecting laterally from the main casing is a laterally swingable arm 67 (Figs. 2, 6, 8, 9, 14, 16 and 17) the forward end of which has an opening 68 to receive the wire W from a spool (not shown) and also has a spring-pressed holding pawl 69 to engage and carry the wire 65 on the feeding stroke of the arm and to re-

lease it on the back stroke in a well known way. The wire feeding operation immediately follows the final button feeding operation just described and to accomplish this the arm is swung laterally toward the button to thread the wire through the eye of the button in the following manner. Projecting downwardly from the lower side of the arm 67 near the pivotal point thereof is a spring-pressed pin 70, the spring being 70 shown in dotted lines in Fig. 14. Projecting laterally from the main operating lever is a block 71 having on the outer edge thereof an upwardly projecting wall 72 the inner 75 face of which is provided with a cam surface 73. The wall 72 near its rear end is inclined downwardly as shown in Figs. 6, 14 and 16 and opposite this downwardly inclined part of the wall is an upwardly projecting cam 74. As a result of this construction, when the main operating lever is thrown forwardly the cam surface 73, contacting the pin 70, moves the arm 67 laterally so as to feed the wire through the eye 80 of the button which has been placed in proper position by the initial operation of the main operating lever. Upon further movement of the main operating lever the pin will contact the cam surface 74 so as to throw the arm 67 back to its original 85 position, which will, by reason of the downward inclination of the wall 72, bring the lower end of the pin above the wall so that when the main operating lever returns to its normal position the pin will ride over that 90 part of the wall in line with the cam surface 73, the pin yielding against the tension of its spring for this purpose, and will again drop into its proper normal position to be again acted upon by the cam 73 upon 95 the next operation of the machine. It should be explained that while the pin is traveling upon the inner surface of the wall between the cam surface 73 and the cam surface 74, the severing of the wire is being 100 accomplished, this severing operation being 105 described hereinafter.

Cut out for wire feed.

In the event that a button is not in position to be fed upon the initial operation of the machine, or in the event that the button feed finger fails to feed a button, it is desirable that the wire feeding mechanism be thrown out of operation to prevent waste of 115 wire and also clogging of the stapling mechanism. This is accomplished as follows: Upon the initial operation of the machine, it will be remembered that the shaft 60 is released and the finger 61 operated to 120 cause its end 61^a to rest on top of a button which, of course, arrests the rotary movement of the shaft 60. Now, in the event that no button should be in the chute or the 125 raceway, it will be seen that the shaft 60 will 130

be allowed a further rotary movement, which causes the bent end 60^a thereof to strike the projecting finger 75 of a pivoted frame 76 supported on the top of the main 5 casing (Figs. 2, 6, 9 and 13) thus rocking the frame. The opposite end of the frame has a downwardly projecting arm 77, (see also Figs. 14 and 16) the lower end of which will strike a pivoted lever 78, one end 10 of which is bent laterally as indicated at 78^a, so as to bring this part 78^a in close proximity to the lower end of the pin 70, as shown in Fig. 16, the normal position of the parts being shown in Fig. 14. Projecting 15 inwardly from the wall 72 of the block 71 is a cam 79, the pin 70 normally lying out of the path of movement of this cam as the operating lever is moved. When the part 78^a, however, is interposed between the pin 20 and the cam, the cam will throw the pin 70 upwardly against the tension of its spring and thus cause it to ride over the wall 72 instead of about the cam 73 with the result that the wire feeding arm 67 will not be 25 operated.

Staple forming mechanism, (Figs. 10, 11 and 17).

In the normal inoperative position of the 30 mechanism, the wire which is fed by the feeding arm 67 normally lies in a perforation in the portion 3^a of the main casing and in a perforation formed in a shearing die 80 secured to the main casing, the end of 35 the wire being flush with the inner side of the shearing die. Upon the feeding stroke of the arm 67 the wire will be projected across the stapling mechanism now to be described and through the eye of the button 40 which has been fed to proper position by the finger 61 previously described. Slidably mounted in a grooveway 81 formed in the top of the main casing is a plunger 82, the lower half of which is reduced in width 45 and slides between the shearing die 80 and a stop block 83 secured to the main casing. So soon as the wire has been fed to its proper position this plunger 82 is moved downwardly by the main operating lever 50. Secured to the top of the operating lever 20 by dowel pins 84 is a hardened steel plate 85, the rear upper edge thereof having an upwardly and forwardly extending finger 86 which contacts the rear side of a 55 downwardly projecting portion 82^a of the plunger 82 so as to move the plunger downwardly. The forward edge of the plunger 82, coacting with the shearing die 80, severs the wire and further movement of the plunger 82 bends the wire about a former 87, which is in the nature of an extension projecting upwardly from a pivoted lever 88, pivoted at 89 to the main casing 3; the 60 former being held in its proper operative 65 position at this time by a beveled stud 90

on the main operating lever, this being accomplished by the fact that one of the beveled surfaces of the stud rides along the edge 88^b of a tail 88^a projecting from the lever 88, the edge of the tail being formed 70 on the arc of a circle which is concentric to the pivot 59 of the main operating lever. The plunger 82 it will be seen is provided with a centrally arranged slot 91 which embraces the former 87 and the walls of this 75 slot are provided with grooves 92 (shown in dotted lines in Fig. 17 and also in Fig. 10) to receive the wire. Further movement of the operating lever causes the tail 88^a of the lever 88 to ride off of the beveled stud 90, 80 permitting the forming lever 88 to drop to the dotted line position shown in Fig. 11, the opposite beveled surface of the stud 90 riding along the forward edge 88^c of the lever 88. It should be explained that that 85 portion of the shoe to which the button is to be set is laid against the inner edge of an anvil 93 of hardened steel which is carried by a projection 94 preferably formed integral with the main casing. So soon as the 90 plunger 82 has been projected to the proper distance to form the staple, the finger 86 will ride off of the rear end of the projection 82^a of the plunger and contact the inner wall 95 of a groove formed in a block 96, 95 which is slidably mounted upon two pins 97 carried by and projecting rearwardly from the plunger 82, coil springs 98 being interposed between the plunger 82 and the block 96. Further movement of the main 100 operating lever, then, will carry the plunger downwardly against the shoe with a yielding pressure so as to hold the shoe firmly against the anvil 93 and at the same time carries the staple and button down to proper 105 position to be operated upon by the driver which forces the staple through the material of the shoe and clenches it. This driver is in the nature of an arm 99 projecting upwardly and forwardly from the plate 85, 110 the upper edge thereof being formed with a flaring centrally-arranged groove 100 (Fig. 17) and the side thereof with projections 101 which enter the grooveways 92 in the plunger. Further movement of the main operating lever causes this driver to engage the staple, with the groove 100 straddling the eye of the button, and drive the staple through the material of the shoe, the free 115 ends of the staple entering a cross-cut or 120 groove in the anvil so as to bend the same inwardly to properly clamp the staple. The stapling mechanism is covered by a plate 105, as shown in Figs. 2, 8, and 9, formed with a slot 107 to expose the lower portion 125 of the stapling devices so as to allow the buttons from the chutes to be fed thereto; the plate having grooves 108 leading to the slotted portion to accommodate the eyes of 130 the buttons in the chutes. The plate may

also have an extension 106 to retain the forward end of the feed lever on its support from the main casing.

The main operating lever is manipulated by a foot lever 102 (Fig. 1) pivoted at the lower end of the pedestal 1 and hinged to the projecting arm 20^a of the main operating lever by a rod 103, a coil spring 104, one end of which is connected to the foot lever and the other end to the pedestal, serving to return the parts to normal position. So soon as pressure is released from the foot lever, the main operating lever 20 will be caused to move back to normal position. The stud 90, moving down the surface 88^c of the forming lever, forces the same upwardly to its normal forming position. The driving arm 99 of the plate 85, contacting the block 82 forces it back to its normal position, the finger 86 leaving the wall 95 of the auxiliary block 96 and assuming its original position back of the projection 82^a; the final button feed is returned to its normal position in the manner previously described; the feed arm 67 has already been returned to its normal position prior to the clenching operation, and in this connection it should be stated that a pivoted spring-pressed holding pawl 109 (Fig. 17) is provided to retain the wire 13 in the block 3^a and die 80 in proper position during the return movement of the feeding lever. The reverse stroke of the main operating lever also returns the operating rod 13 for the feed wheel in the hopper to its normal position by reason of the camway 19 previously described.

By the constructions described it will be seen that by the arrangement of the double raceways or chutes, the machine may be readily altered for the purpose of setting odd sized buttons without the necessity of removing any of the parts by simply manipulating the crank arm to throw the chutes and hopper laterally from one position to another. It will also be seen that the raceways and hopper may be readily tilted rearwardly to remove the buttons from the hopper and chutes and that it will become automatically locked when thrown back to normal position. By the arrangement described, whereby the entire operation of setting the button is performed upon the down stroke of the foot lever, an improved arrangement is provided which will obviate the necessity of removing a button and staple from the machine in the event that it is desired to change from one chute to another, as is the case with those machines which feed and thread a button upon the return movement of the operating devices to normal position. Further, the arrangement whereby all of the operating devices are operated by the down stroke of the foot lever provides for less power to manipulate the devices by reason of the fact that a lighter

spring may be employed to return the parts to normal position than would be the case if it was necessary to rely upon the spring to perform certain of the operations, such as the feeding of the buttons and wire. 70

Having thus described our invention, we claim:

1. In a machine of the character described, the combination of a movable hopper, stapling mechanism, a plurality of associated raceways movable with said hopper one of which is normally in communication with the interior of said hopper, with all of said raceways extending to said stapling mechanism, means for shifting said hopper and raceways to bring one of said raceways in proper feeding relation to said stapling mechanism, and means for feeding a button and length of wire to said stapling mechanism upon the initial movement of the machine whereby in the inoperative condition of said machine said stapling mechanism is free from a button and its wire. 80

2. In a machine of the character described, a movable hopper, a plurality of raceways movable with said hopper, one of said raceways being in communication with the interior of said hopper, stapling mechanism to which said raceways extend, and means for moving said hopper and raceways laterally and also for raising said raceways above said stapling mechanism during such movement to bring one or the other of said raceways in proper feeding relation to said mechanism. 90

3. In a machine of the character described, a hinged hopper capable of lateral movement, a plurality of raceways connected with said hopper to partake of its movement, one of said raceways being in communication with the interior of said hopper, stapling mechanism to which said raceways extend, and means for moving said hopper and raceways laterally and also swinging said hopper about its hinge to enable the raceways to clear the stapling mechanism during such lateral movement for the purpose of bringing either one or the other of said raceways in feeding relation with said stapling mechanism. 105

4. In a machine of the character described, the combination of a movable hopper, stapling mechanism, a plurality of raceways movable with said hopper with one of the raceways in communication with the interior of said hopper and both raceways extending to said stapling mechanism, means for moving said hopper and raceways laterally to bring one of said raceways in proper feeding relation to said stapling mechanism, and means for feeding a button and length of wire to said stapling mechanism upon the initial operation of the machine whereby said stapling mechanism will normally be free from a button and its staple wire. 110

5. In a machine of the character described, a movable hopper, a pair of raceways movable with said hopper, one of said raceways being in communication with the 5 interior of said hopper, stapling mechanism to which said raceways extend, and means for moving said hopper and raceways laterally and also for raising said raceways above said stapling mechanism during such 10 movement to bring one or the other of said raceways in proper feeding relation to said mechanism, and means for feeding a button and length of wire to said stapling mechanism upon the initial operation of the 15 machine whereby said stapling mechanism will normally be free from a button and its staple wire to permit shifting of the raceways from one position to another.

6. In a machine of the character described, a hinged hopper capable of lateral movement, a pair of raceways connected with said hopper to partake of its movement, one of said raceways being in communication with the interior of said hopper, 20 stapling mechanism to which said raceways extend, means for moving said hopper and raceways laterally and also swinging said hopper about its hinge to enable the raceways to clear the stapling mechanism during 25 such lateral movement for the purpose of bringing either one or the other of said raceways in feeding relation with said stapling mechanism, and means for feeding a button and length of wire to said stapling 30 mechanism upon the initial operation of the machine whereby said stapling mechanism will normally be free from a button and its staple wire to permit shifting of the raceways from one position to another.

40 7. In a machine of the character described, a hopper hinged to swing upwardly and capable of lateral movement upon its hinge, a plurality of raceways connected with said hopper, a stapling mechanism to 45 which said raceways lead, and a rotatable shifting device comprising means for shifting said hopper and raceways laterally and also for swinging the same about the hinge of said hopper to clear the lower end of the 50 raceways from said stapling mechanism during the shifting movement.

8. In a machine of the character described, a hopper hinged to swing upwardly and also capable of lateral movement upon 55 its hinge, a plurality of raceways connected

with said hopper, a stapling mechanism to which said raceways lead, and a rotatable shifting device for said hopper and raceways comprising an eccentric and crank arm for imparting a lateral and upwardly 60 swinging movement to said hopper and raceways.

9. In a machine of the character described, a main operating device, wire feeding devices, and button feeding devices, said 65 button feeding devices comprising a rotatable spring-pressed shaft, a button engaging member arranged to engage the top of a button, a detent for said shaft, and connections operated by said shaft whereby an abnormal movement of said shaft to button 70 engaging position throws said wire feeding devices out of operation.

10. In a machine of the character referred to, button feeding devices, wire feeding devices, said wire feeding devices comprising a movable arm having a spring-pressed operating pin together with means for engaging said pin to swing said arm, and means operated by an abnormal movement of said 80 button feeding devices for throwing said pin out of operative position.

11. In a machine of the character described, button feeding devices, wire feeding devices, said wire feeding devices comprising a movable arm having a spring-pressed operating pin, a cam for engaging said pin to swing said arm, and means operated by an abnormal movement of said 85 button feeding devices for throwing said pin 90 out of the path of said cam.

12. In a machine of the character described, wire feeding devices comprising a movable arm, a spring-pressed pin carried by said arm, a main operating device, a pair 95 of cams operated by said device, one cam for throwing said arm to feeding position and the other cam for returning said arm to normal position, and an inclined track for said pin movable with said main operating device upon the return of the parts to normal position.

In testimony whereof we have hereunto set our hands this 14th day of August, 1917.
